UNITED STATES PATENT OFFICE

PETER RICHIE, OF WATERBURY, CONNECTICUT

PENCIL ATTACHMENT

Application filed June 25, 1928. Serial No. 288,098.

This invention relates to pen and pencil attachments, and more particularly to an attachment of this nature comprising a combination finger rest and pocket clip.

5 One object of this invention is to provide a device of the above nature in which the finger rest will afford a comfortable gripping section for the forefinger of the writer, and in which said section will prevent rolling of the pen or pencil when laid upon a desk.

A further object is to provide a device of the above nature which when used on a pen will positively hold it in correct writing 15 position at all times without twisting.

A further object is to provide a device of the above nature which will shield the finger of the writer from being soiled by the inked portion of a pen.

20 A further object is to provide a device of the above nature which will be simple in construction, inexpensive to manufacture, compact, ornamental in appearance, and very efficient and durable in use.

25 With these and other objects in view, there has been illustrated on the accompanying drawings one form in which the invention may be conveniently embodied in practice.

30 Fig. 1 represents a plan view of the blank from which the combination finger rest and pocket clip is constructed.

Fig. 2 is a perspective view of the completed pencil attachment after it has been 35 bent up from the blank shown in Fig. 1.

Fig. 3 is a transverse sectional view of the pencil attachment as it appears when in position upon a pencil.

Fig. 4 is a side view of the attachment 40 as it appears when mounted on a pencil and held in the hand of the writer.

It is well known that when writing with a pen or pencil, the fingers of the writer soon before fatigued and uncomfortable— 45 more especially in the case of pencils of small diameter and having sharp corners. By means of the present invention the above and other disadvantages have been avoided. This has been accomplished by providing 50 an attachment having a wide comfortable

finger rest spaced from the axis of the pencil, said attachment also having a clip for engagement with the edge of a pocket.

Referring now to the drawings in which like reference numerals denote corresponding parts throughout the several views, the first step in the manufacture of the combination attachment is to stamp out a T-shaped metal blank in the shape shown in Fig. 1. Referring to said figure it will be seen that said blank has a pair of opposed horizontal rectangular side wings 10 and 11 provided with curved extremities, said wings 10 and 11 being adapted to be bent into oppositely curved outwardly convex 60 circular pencil gripping jaws, as shown in Figs. 2 and 3.

Between the wings 10 and 11 the blank has a body section 12 adapted to form a finger rest when bent into the shape shown 70 in Figs. 2 and 3 with its sides bent forwardly at 13 and 14 and then rearwardly and inwardly into contact with the underside of the section 12 forming loops 15 and 16 which are integrally connected to the curved 75 gripping jaws 10 and 11.

By means of this construction it will be seen that the finger rest 12 is spaced a considerable distance from the axis of the pencil, thereby reducing the cramping of the 80 fingers of the writer's hand and enabling him to write with greater comfort and less fatigue.

In order to still further add to the writer's comfort, the upper extremity 17 of the attachment is bent rearwardly slightly to form a support for the tip of the writer's forefinger, as clearly shown in Figs. 2 and 4. Provision is also made of a pocket clip 18 integrally connected with and depending 85 from the body section 12, said clip 18 having a depressed section 19 adapted to lie in contact with a pencil 20. The depressed section 19 serves to form a more rigid support for the finger rest and also to effectually clamp the pocket when the pencil is not in use. The extremity 21 of the clip 18 is bent outwardly away from the axis of the pencil and serves to facilitate the forcing of 90 the clip over the edge of the pocket. 95

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

- 15 1. In a combination pencil clip and finger rest, a pair of pencil gripping jaws, and a longitudinal finger supporting section spaced from the axis of the pencil and integrally connected to said jaws by a pair of loops, said loops being in contact with the underside of said finger supporting section to form a base therefor.
- 20 2. In a combination pencil clip and finger rest, a pair of pencil gripping jaws, a finger supporting section connected to said jaws by a pair of loops, and a forwardly extending extremity on said finger supporting section to form a rest for the tip of the writer's forefinger.

30 In testimony whereof, I have affixed my signature to this specification.

PETER RICHIE.
